METHOD AND APPARATUS FOR DIELECTRIC HEATING

George E. Gard, Lancaster, Pa., assignor to Armstrong Cork Company, Lancaster, Pa., a corporation of Pennsylvania

Application January 24, 1947, Serial No. 724,186

14 Claims. (Cl. 219—47)

1

This invention relates to dielectric heating and, in particular, to a method and apparatus for maintaining substantially uniform distribution of the lines of force through the mass to be heated.

In heating certain masses by dielectric effect the distribution of the lines of force through the mass is not uniform and the rate of generating heat differs in various portions of the mass. This is undesirable in many cases where uniform heating throughout the mass is necessary to obtain a uniform product. The non-uniform distribution of lines of force is increased when the mass has a dimension normal to the usual electrode plates which is of the same order as or greater than the transverse dimension. In such cases, the lines of force through the mass are spread farther apart adjacent the median transverse plane than at the surfaces of the electrodes. As a result, more heat is generated adjacent the electrodes than in the intermediate portion of the mass.

I have invented a novel method and apparatus for dielectric heating whereby substantially uniform distribution of the lines of force through the mass to be heated may be obtained even though the dimension of the mass normal to the electrodes is several times the other dimension. In a preferred embodiment, I provide a voltage divider coil in the form of a helix surrounding the mass to be heated, and connect the ends of the coil to the electrodes, thus placing the inductance of the coil in parallel with the capacity of the mass to be heated. The inductance thus tends to balance the load capacity. It also reduces the non-uniformity of distribution of the lines of force through the mass which would exist if the mass were outside of the coil. By properly spacing the successive turns of the coil, a high degree of uniformity in the distribution of lines of force may be obtained.

A complete understanding of the invention may be obtained from the following detailed description and explanation which refer to the accompanying drawing illustrating a preferred embodiment and certain modifications. In the drawings,

Figure 1 is a plan view;

Figure 2 is a section therethrough taken along the plane of line II—II of Figure 1;

Figure 3 is a view similar to Figure 2 showing a modification; and

Figure 4 is a view of the cross-section of the embodiment in Figure 1, illustrating closer

2

spacing of the successive coil turns adjacent the top and bottom portions of the mass.

Referring in detail to the drawings and, for the present, to Figures 1 and 2, a mass 10 of dielectric material to be heated is disposed between spaced electrode plates 11 and 12. An insulating layer 13 is disposed between the mass and each electrode plate. If the mass is composed of flowable material, e. g., cork particles coated with a heat-activatable binder, adapted to be converted into a solid mass of cork composition, it is preferably confined in a mold 14 of which the electrode plates 11 and 12 serve as the top and bottom, respectively. The mold may be of any suitable shape or dimensions. In the form illustrated, it is a cylinder composed of laminated paper impregnated with ceresin wax so as to have a loss factor equal to or greater than that of the material of which the mass 10 is composed. A mold having a loss factor equal to or greater than the material to be dielectrically heated is disclosed and claimed in my copending application Serial No. 678,217 filed June 21, 1946, and entitled Method of Controlling Dielectric Heating (Prevention of Heat Loss). Dielectric heating equipment including a mold having a wax impregnant such as ceresin is disclosed and claimed in the copending application of George W. Scott, Jr., Serial No. 678,215, filed June 21, 1946, and entitled Method and Apparatus for Dielectric Heating. In the curing of cork composition, the coated cork particles are compressed between the electrode plates and the latter are held in position by through pins 15 inserted through holes in the mold wall.

A voltage divider in the form of a helix 16 of any suitable conductor is disposed about the mold 14 and preferably in contact therewith or partly or wholly embedded therein. The ends of the helix are electrically connected to the electrode plates. In the illustrated embodiment, the end turns of the helix are in contact with the pins 15 which are of metal and are also in contact with the electrode plates 11 and 12. A source of high-frequency current 17 such as a vacuum-tube oscillator is connected across the electrode plates and the coil 16 in parallel therewith by conductors attached to the pins 15. The coil and plates may, of course, be separately connected in parallel to the source if desired. If the inductance of the coil 16 is greater than needed to balance the capacity of the mass 10, in order to produce a condition of parallel resonance, a variable inductance 18 may be connected in parallel with

the load and the coil 16 to reduce the overall inductance for the purpose of tuning the circuit to resonance.

The coil 16 connected to the source of high-frequency 17 for dielectrically heating the mass 10 constitutes a very much higher impedance than the mass. At the relatively high frequencies employed in dielectric heating work, the stray capacitance between the mass 10 and the coil 16 capacitatively couples all points of the coil 16 to the mass 10, and there is thus provided a voltage divider which is capacitatively coupled to the mass at an infinite number of points.

The coil 16 performs two important functions. In the first place, it serves to maintain substantially uniform distribution of the electric lines of force through the mass 10 between the electrode plates 11 and 12. This improves the uniformity of heating throughout all portions of the mass. This action results from the fact that the voltage divider coil 16 confines within its turns the high-frequency electric field of the condenser formed of the electrode plates 11 and 12 separated by the mass 10 to be dielectrically heated. The second function results from the fact that, because of the impedance constituted by various sections of the voltage divider 16 all connected in series, there is brought about a uniform voltage gradient therealong when the turns are uniformly spaced, and the voltage gradient in the coil determines the position of the equipotential surfaces through the mass. This follows from the fact that the voltage divider establishes a high-frequency boundary potential distribution in the space closely adjacent to and surrounding the mass; and where the turns of the voltage divider coil 16 are equally spaced, its impedance value will be uniform along its length, and it will possess a uniform voltage gradient which will establish a similar gradient within the mass, for the voltage divider controls the electric field between the electrodes in accordance with its voltage gradient. This gradient may be varied by changing the spacing of the coil turns in various portions of its length to produce a substantially uniform temperature in the mass. Where the turns of the voltage divider coil 16 are spaced closer together, the impedance value will be higher, and a proportionately greater voltage drop will occur. Thus, the voltage gradient will be nonuniform and a higher heating rate will be obtained in the mass in the zones where the voltage drop in the voltage divider coil 16 is greater because, as mentioned above, the voltage gradient of the coil controls the electric field within the mass. Thus, if it is desired to heat one portion of the mass to a higher temperature than another, this result may be accomplished by properly distributing the turns of the coil, thereby changing the voltage gradient or electric field within the mass.

The coil 16 being in contact with the surface of the mold 14 or partially or wholly embedded therein serves also as a mechanical reinforcement therefor. This is important because of the fact that most materials having a loss factor low enough to make them suitable for a mold for dielectric heating, also exhibit a low tensile strength. The reinforcing effect of the coil 16 thus permits the pressure on the mass 10 to be increased or the thickness of the mold wall decreased. The latter is particularly desirable to reduce the amount of energy consumed in heating the mold itself as contrasted with the contents thereof.

The coil 16, of course, produces a high-

frequency electromagnetic field longitudinally through the mold 10. This field tends to heat the electrode plates 11 and 12 by induction. While some heating of the electrode plates is desirable to prevent excessive loss of heat thereto from the mass 10, overheating of the electrode plates is undesirable because of the danger of overcuring the top and bottom of the mass or even charring it. To avoid this, I provide the electrode plates 11 and 12 which may conveniently be composed of steel, with peripheral rings or bands 19 of copper or other suitable material having a conductivity much greater than that of the metal of which the plates themselves are composed. The copper rings act in the known manner to shield the electrode plates from the electromagnetic field. The alternating electromagnetic field thus induces current largely in the rings 19 rather than in the electrode plates themselves.

In using the apparatus described above for performing the method of my invention, the mold 14 is filled by the aid of a so-called charging boot with the electrode 11 and upper insulating layer 13 removed. The insulating layer and electrode plate are then placed on top of the charge and it is compressed to the desired degree after which the upper pins 15 are inserted to hold the plate in place. High-frequency voltage is then applied as by closing a switch 20. When the mass has been heated sufficiently, the switch is opened, the plate 11 and upper insulating layer are removed and the mass is then pushed out of the mold.

Figure 3 illustrates a modification of the apparatus already described. The modified apparatus is adapted to be used between the platens 21 and 22 of a press instead of relying on through pins to hold and confine the material. As shown in Figure 3, a bottom electrode plate 23 is disposed on the platen 22. A top electrode plate 24 carried on the upper platen 21 is adapted to enter a mold 25 and compress a charge of material 26 therein. Insulating layers are disposed between the electrode plates and the material to be heated. The mold 25 may be similar in construction to the mold 14 and is provided with a surrounding helix 27 which serves as an inductance to balance the load capacity, having its ends connected to the electrode plates 23 and 24, respectively. In other respects, the arrangement shown in Figure 3 is similar to that of Figure 2.

Figure 4 illustrates the embodiment shown in Figures 1 and 2 with, however, closer spacing of the successive turns of the coil 16 along the top and bottom portions of the mass 10 than the spacing of the turns adjacent the intermediate portions of the mass. By such spacing, a proportionately greater voltage drop with consequently greater dielectric heating is achieved in the transverse portions of the mass at the top and bottom within the space surrounded by the closer spaced turns. In this way, a more uniform temperature of the mass 10 is obtained in areas of uneven and possibly greater heat loss as by conduction through the electrodes. Moreover, by presetting such spacing as and where desired along the length of the mass, variations from the uniform which may be wanted under special circumstances can also be achieved.

It will be apparent from the foregoing description that the invention provides a method and apparatus for dielectric heating having several important advantages. In the first place, the disposition of the charge to be heated within the voltage divider permits the maintenance of the

desired distribution of lines of force or position of the equipotential surfaces through the mass. In the second place the voltage divider controls the electric field within the mass between the electrode plates in accordance with its voltage gradient and permits controlled heating of the mass to obtain a substantially uniform temperature in the mass or a higher temperature in one portion of the mass than in another. In addition, the helix forming the inductance serves mechanically to reinforce the mold wall, permitting a reduction in the section thereof without seriously weakening it. A more uniform product is thus obtainable by the use of the invention without materially increasing the cost of the apparatus or complicating the normal operating procedure.

Although I have illustrated and described but a preferred embodiment and practice of the invention, it will be recognized that changes in the apparatus and procedure disclosed may be made without departing from the spirit of the invention or the scope of the appended claims.

I claim:

1. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass between said electrode plates, and means for controlling the voltage gradient within said mass between said electrode plates comprising a voltage divider coupled to said high-frequency current source and disposed closely adjacent to and surrounding said mass between said electrode plates.

2. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass, and means for controlling the voltage gradient within said mass between said plates comprising a voltage divider coil having a plurality of turns disposed closely adjacent to and surrounding said mass between said electrode plates and coupled to said high-frequency current source.

3. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass, and means for limiting the distribution of the electric lines of force of said field essentially to within said mass between said electrode plates and for controlling the voltage gradient within said mass between said electrode plates comprising a voltage divider providing a plurality of closely spaced conducting surfaces disposed closely adjacent to and surrounding said mass between said electrode plates and coupled to said high-frequency current source.

4. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within

said mass, and means for limiting the distribution of the electric lines of force of said field essentially to within said mass between said electrode plates comprising a voltage divider coil having a plurality of closely spaced turns disposed closely adjacent to and surrounding said mass between said electrode plates and connected to said electrode plates in parallel therewith.

5. Apparatus for dielectrically heating a mass of dielectric material comprising a nonconductive container for said mass, electrode plates closing said container and adapted to confine said mass within said container, means for supplying high-frequency alternating electric current to said electrode plates from a source to establish a high-frequency electric field within said mass, and means for controlling the voltage gradient within said mass between said electrode plates comprising a voltage divider coupled to said high-frequency current source and disposed closely adjacent to and surrounding said mass between said electrode plates.

6. Apparatus for dielectrically heating a mass of dielectric material comprising a nonconductive mold for said mass, substantially parallel electrode plates closing said mold and adapted to be positioned on opposite sides of said mass within said mold, means for supplying high-frequency alternating electric current to said electrode plates from a source to establish a high-frequency electric field within said mass, and means for limiting said field essentially to within said mass and for controlling the voltage gradient within said mass between said electrode plates comprising a voltage divider coil having a plurality of closely spaced turns between said electrode plates which are disposed closely adjacent to and surround said mold and are connected to said electrode plates in parallel therewith.

7. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass, and means for controlling the voltage gradient within said mass between said electrode plates comprising a voltage divider coupled to said high-frequency current source and disposed closely adjacent to and surrounding said mass between said electrode plates, said voltage divider having its conducting surfaces nonuniformly spaced to provide a nonuniform voltage gradient in the voltage divider and in the electric field.

8. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass, and means for controlling the voltage gradient within said mass between said electrode plates comprising a voltage divider coil having a plurality of turns disposed closely adjacent to and surrounding said mass between said electrode plates, and means connecting said voltage divider coil to said electrode plates in parallel therewith to establish a tuned high-frequency resonant circuit with said voltage divider coil and the capacitance between said electrode plates.

9. Apparatus for dielectrically heating a mass

of dielectric material comprising a pair of substantially parallel electrode plates adapted to be positioned on opposite sides of said mass, means for supplying high-frequency alternating electric current to said electrode plates from a source to establish a high-frequency electric field within said mass, means for controlling the voltage gradient within said mass between said electrode plates comprising a voltage divider coupled to said high-frequency current source and disposed closely adjacent to and surrounding said mass between said electrode plates, and a variable inductance connected in parallel with said electrode plates for tuning the high-frequency alternating electric current circuit to resonance.

10. Apparatus for dielectrically heating a mass of dielectric material comprising a pair of substantially parallel electrode plates adapted to be positioned on opposite sides of said mass, means for supplying high-frequency alternating electric current to said electrode plates from a source to establish a high-frequency electric field within said mass, means for controlling the voltage gradient within said mass between said electrode plates comprising a voltage divider coil having a plurality of closely spaced turns between said electrode plates which are disposed closely adjacent to and surrounding said mass and connected to said electrode plates in parallel therewith, and a metal conductor of lower electrical impedance than said electrode plates disposed adjacent to and surrounding each of said electrode plates and electrically connected thereto.

11. In a process of dielectrically heating a mass of dielectric material disposed between spaced electrode plates, the steps of establishing a high-frequency alternating electric field within said mass between said electrode plates to dielectrically heat the mass and controlling the electric field within the mass between said spaced electrode plates by establishing a high-frequency boundary potential distribution in the space around said mass between said electrode plates closely adjacent to said mass.

12. In a process of dielectrically heating a mass of dielectric material disposed between spaced electrode plates, the steps of establishing a high-frequency alternating electric field within said mass between said electrode plates to dielec-

trically heat the mass and controlling the electric field within the mass between said electrode plates by establishing a high-frequency boundary potential distribution in the space around said mass between said electrode plates closely adjacent to said mass having a voltage gradient therealong which is predetermined in accordance with the voltage gradient desired within said mass between said electrode plates.

10. 13. In a process of dielectrically heating a mass of dielectric material disposed between spaced electrode plates, the steps of establishing a high-frequency alternating electric field within said mass between said electrode plates to dielectrically heat the mass and controlling the electric field within the mass between said electrode plates by establishing a nonuniform high-frequency boundary potential distribution in the space around said mass between said electrode plates.

15. 14. In a process of dielectrically heating a mass of dielectric material disposed between spaced electrode plates, the steps of establishing a high-frequency alternating electric field within said mass between said electrode plates to dielectrically heat the mass and controlling the electric field within the mass between said electrode plates by establishing a nonuniform high-frequency boundary potential distribution in the space around said mass between said electrode plates closely adjacent to said mass to effect predetermined voltage drops within said mass in accordance with the voltage drops in said boundary potential distribution.

20. 15. In a process of dielectrically heating a mass of dielectric material disposed between spaced electrode plates, the steps of establishing a high-frequency alternating electric field within said mass between said electrode plates to dielectrically heat the mass and confining and controlling the electric field within the mass between said electrode plates by positioning a voltage divider electrically connected to said electrode plates closely adjacent to and surrounding said mass between said electrode plates to establish 30 an arbitrary high-frequency boundary potential distribution closely adjacent to said mass.
